US0D1095527S

(12) **United States Design Patent** (10) Patent No.: **US D1,095,527 S**
(45) Date of Patent: ** Sep. 30, 2025

(54) **HEADSET**

(71) Applicant: **XENON OPHTHALMICS INC.**,
Belleville, NJ (US)

(72) Inventors: **Mario A Turchi**, Tenafly, NJ (US);
Thomas Van Dyk, Ramsey, NJ (US)

(73) Assignee: **XENON OPHTHALMICS I INC.**,
Belleville, NJ (US)

(**) Term: **15 Years**

(21) Appl. No.: **29/928,030**

(22) Filed: **Feb. 7, 2024**

Related U.S. Application Data

(62) Division of application No. 29/829,227, filed on Mar. 3, 2022, now Pat. No. Des. 1,019,641.

(57) **CLAIM**

The ornamental design for a headset as shown and described.

DESCRIPTION

FIGS. 1-8 illustrate a headset in which FIG. 1 is a front perspective view thereof;

FIG. 2 is front elevation thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a rear perspective view thereof.

The broken lines in the figures are for the purpose of illustrating environmental structure and form no part of the claimed design.

1 Claim, 8 Drawing Sheets
